CLAIM

The ornamental design for jaws for folding pliers, as shown and described.

DESCRIPTION

FIG. 1 is an isometric view from the upper right front of a pair of jaws for folding pliers showing my new design, in a closed position;

FIG. 2 is an isometric view from the upper right front of the pair of jaws shown in FIG. 1, in an opened position;

FIG. 3 is a right side elevational view of the jaws as shown in FIG. 1, the left side elevational view thereof being identical thereto;

FIG. 4 is a top plan view thereof, the bottom plan view thereof being identical thereto;

FIG. 5 is a rear end elevational view thereof; and,
FIG. 6 is a front end elevational view thereof.
